UNITED STATES PATENT OFFICE

WILHELM GERMANN, OF DORTMUND, GERMANY, ASSIGNOR TO THE FIRM VEREINIGTE STAHLWERKE AKTIENGESELLSCHAFT, OF DUSSELDORF, GERMANY

DOUBLE SLIP POINT

Application filed October 30, 1930, Serial No. 492,299, and in Germany November 9, 1929.

The invention relates to another improvement of the double slip point according to my prior application Serial No. 488,481, filed October 13, 1930. In this prior application a 5 double slip point with tongues disposed outside the diamond has been disclosed which is characterized by the fact that the centre piece of rail which is passed over by the rolling stock on both sides is formed by a rail-like 10 rolled section having a width of its head large enough to enable the curved running edges to be machined-in laterally.

Furthermore, according to the prior application, the said rolled section may be used for 15 manufacturing the three frogs of the double slip point.

The invention represents a broader aspect 20 of the principle of using the rolled bar forming the centre piece of rail of the switch for manufacturing the other parts of the switch, also the counter-point of the switch being formed, according to the invention, by the rail-shaped rolled section.

As compared with the now nearly exclusively adopted practice of manufacturing 25 this part by casting the present invention represents a considerable economy and simplification in the production of the entire double slip point, since all parts, excepting the tongues, may now be manufactured from 30 the same rolled section.

According to the invention the counter-point is formed in such a way that the centre rail of the switch which is passed over by the 35 rolling stock on both sides is split at its end, spread apart and bent, in addition thereto the rolled section being pointed according to the shape of the counter-point. This means that the centre piece of rail as well as the counter-point form one single piece, the centre piece of rail preferably being subdivided at half its length.

The invention also comprises the construction 45 of the counter-point as a separate part which is attached to the centre piece of rail. The manufacture is effected in much the same way by splitting, spreading apart and bending from the rolled section which also forms the centre piece of rail.

The drawing shows two constructional examples of the invention.

In Fig. 1 the counter-point 1 of the double slip point is integral with the centre rail 2. The rail-like rolled section forming the centre rail is correspondingly split at its end, spread apart and bent, whereby the counter-point is produced. 55

According to Fig. 2 the counter-point forms a separate part which at A adjoins to the centre rail and is produced from the same rolled section as the centre piece of the switch by suitable machining. 60

Having thus described my invention what I claim as new and desire to secure by Letters Patent is: 65

1. A double slip point characterized by the fact that the centre piece of rail which is passed over by the rolling stock of both sides is formed from a rail-like rolled section having a great width of head portion and split at its ends, spread apart and bent and that thereby and by pointing the rolled section according to the shape of the counterpoint, the counter-points of the switch are formed. 70 75

2. A device according to claim 1 characterized by the fact that the centre piece with counter-point is subdivided at about the centre. 80

3. A device according to claim 1 characterized by the fact that the counter-points are formed as separate parts and are manufactured from the same rolled section as the centre piece of the switch by splitting, spreading apart and bending. 85

In testimony whereof I affix my signature.

WILHELM GERMANN.
